US00D470450S

(12) **United States Design Patent**
Olzak

(10) Patent No.: **US D470,450 S**
(45) Date of Patent: ** Feb. 18, 2003

(54) **ENCLOSURE FOR CRASH SURVIVABLE
DATA RECORDER**

D425,506 S * 5/2000 Olzak et al. D14/167
6,153,720 A * 11/2000 Olzak et al. 528/182

(75) Inventor: **Richard Olzak**, Kirkland, WA (US)

* cited by examiner

(73) Assignee: **Honeywell International Inc.**,
Morristown, NJ (US)

Primary Examiner—Stacia Cadmus

(**) Term: **14 Years**

CLAIM

(21) Appl. No.: **29/142,342**

The ornamental design for enclosure for crash survivable data recorder, as shown and described.

(22) Filed: **May 22, 2001**

DESCRIPTION

(51) LOC (7) Cl. **12-16**

(52) U.S. Cl. **D12/400**; D6/448; D14/168

FIG. 1 is a perspective view of a crash survivable data recorder showing my new design;

FIG. 2 is a top plan view thereof;

FIG. 3 is a bottom plan view thereof;

FIG. 4 is a front elevational view, the rear elevational view being a mirror image thereof;

FIG. 5 is a right side elevational view, the left side elevational view being a mirror image thereof;

FIG. 6 is a perspective view of a second embodiment of the invention;

FIG. 7 is a front elevational view of FIG. 6;

FIG. 8 is a rear elevational view of FIG. 6;

FIG. 9 is a perspective of a third embodiment of the invention;

FIG. 10 is a front elevational view of FIG. 9; and,

FIG. 11 is a rear elevational view of FIG. 9.
